US00D688558S

(12) **United States Design Patent**
Crawford et al.

(10) **Patent No.:** **US D688,558 S**
(45) **Date of Patent:** **** Aug. 27, 2013**

(54) **CONTAINER**

(75) Inventors: **John C. Crawford**, Mahopac, NY (US);
Christopher Hart, Chicago, IL (US);
Stacy Castro, Chicago, IL (US)

(73) Assignee: **Colgate-Palmolive Company**, New York, NY (US)

(**) Term: **14 Years**

(21) Appl. No.: **29/423,997**

(22) Filed: **Jun. 7, 2012**

(51) LOC (9) Cl. **09-01**

(52) U.S. Cl.

USPC **D9/529**; D9/562; D9/565; D9/573;
D9/575; D9/449

(57) **CLAIM**

The ornamental design for a container, as shown and described.

DESCRIPTION

FIG. 1 is a top, front, left side perspective view of a container according to a first embodiment of the new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines shown in the drawings are included for the purpose of illustrating environmental structure and form no part of the claimed design.

1 Claim, 4 Drawing Sheets
